UNITED STATES PATENT OFFICE.

WILLIAM L. CLAYTON AND NEWTON R. PERSINGER, OF CENTRAL CITY,
NEBRASKA.

ATTACHMENT FOR OIL-CONTAINERS.

SPECIFICATION forming part of Letters Patent No. 653,985, dated July 17, 1900.

Application filed September 2, 1899. Serial No. 729,346. (No model.)

To all whom it may concern:

Be it known that we, WILLIAM L. CLAYTON and NEWTON R. PERSINGER, of Central City, in the county of Merrick and State of Nebraska, have invented a new and Improved Attachment for Oil-Containers, of which the following is a full, clear, and exact description.

This invention relates to a device for permitting lamps and other articles to be filled with oil from a can, barrel, or other like container, the oil being forced out by air-pressure; and the invention comprises certain novel constructions for effectively attaining this end.

This specification is the disclosure of two forms of our invention, while the claims define the actual scope thereof.

Reference is to be had to the accompanying drawings, forming a part of this specification, in which similar characters of reference indicate corresponding parts in both the views.

Figure 1 is a side elevation of the invention with parts in section, showing the invention as applied to an oil-can. Fig. 2 is a similar view showing the invention applied to a barrel.

Referring to Fig. 1, the oil-can 3 has a discharge-spout 4, which extends vertically from the bottom of the oil-can upward through a screw-cap 10 and is carried thereby, the tube 4 being formed with a downwardly-projecting spout 5 to deliver the oil into the lamp or other article. A closure 6 for the spout 5 is provided and is held by a chain 7, attached to an eye 8, fastened on the oil-can. When not in use, the closure 6 hangs in the position shown in Fig. 1 of the drawings.

The oil-can is provided with a threaded flange 9, surrounding an opening in the top thereof, and this flange carries the screw-cap 10, on which stands a hollow column 11, this column communicating at its upper end with a valve-chamber 12, such chamber being of approximately double-conical form, the apex of one cone communicating with an air-bulb 14, by means of which air-pressure may be established within the can. A valve 15 is mounted in the chamber 12 and is adapted to be moved into either end thereof across the

mouth of the hollow column 11. The full and dotted lines in Fig. 1 illustrate the positions which this valve 15 is capable of occupying. The valve 15 is provided with a stem 16, which is projected through the end of the valve-casing 12 opposite the end with which the bulb 14 communicates. If so desired, the cap 10 may be unscrewed from the nipple 9 and replaced by an ordinary screw-cap 17, held by a chain 18, one link of which is attached to a rivet on the cap and the other end link of which is attached to the eye 8, before mentioned. The rivet on the cap 17 serves as a swivel to securely hold the cap and yet to allow it to be turned in engaging and disengaging it with and from the nipple.

In using the invention the valve 15 may be thrown to the position shown by full lines in Fig. 1 and the closure 6 disengaged from the nozzle 5. Then by working the bulb 14 an air-pressure is established within the can on top of the oil, and the oil is forced out through the tube 4 and nozzle 5. When it is desired to stop the flow of the oil, the valve 15 is thrown to the position indicated by dotted lines in Fig. 1, which immediately releases air-pressure within the can and at the same time prevents any additional pressure being established by the operation of the bulb 14. Should the lamp or other object have been filled excessively, the spout 5 of the tube 4 may be inserted in the lamp, and by throwing the valve 15 to the position indicated in dotted lines in Fig. 1 the oil may be siphoned back from the lamp to the can, as will be understood. If desired, the bulb 14 may be dispensed with and an elastic tube attached to the valve-chamber. This tube may be taken in the mouth of the user and the air-pressure furnished in this way. By compressing the tube between the fingers it may be closed as the exigencies of the operation may require.

In applying our invention to a barrel 19 (see Fig. 2) a plug 20 is provided in place of the parts 9 and 10 in Fig. 1. With this arrangement the discharge-tube 4 and the tube or hollow column 11 are carried in the plug and communicate with the interior of the valve in the manner shown. Otherwise the construction is the same as that of Fig. 1.

Having thus described our invention, we claim as new and desire to secure by Letters Patent—

1. The combination of a tube or hollow column, a valve-chamber of approximately double-conical form, the valve-chamber being mounted on the tube and communicating with the same at the middle of the valve-chamber, air-pressure devices in connection with one end of the valve-chamber, the other end of the valve-chamber being open to the atmosphere, and a valve mounted in the valve-chamber and reciprocal across the mouth of the tube or hollow column, the valve seating in each end of the valve-chamber to throw the hollow column or tube alternately in communication with the air-pressure devices and with the atmosphere.

2. The combination with a tube or hollow column, of a valve-chamber mounted thereon and communicating therewith at its middle, one end of the valve-chamber being open to the atmosphere, air-pressure devices communicating with the other end of the valve-chamber, and a valve mounted to reciprocate in the valve-chamber and movable over the mouth of the tube or hollow column, the valve seating in either end of the valve-chamber and serving to alternately place the tube in communication with the air-pressure devices and with the atmosphere.

WILLIAM L. CLAYTON.
NEWTON R. PERSINGER.
